Eugene Lucas Inventor

By his Attorney C. Campbell Hume

UNITED STATES PATENT OFFICE.

EUGENE LUCAS, OF BABYLON, NEW YORK.

BUILDING BLOCK.

Original application filed April 1, 1926, Serial No. 99,076. Divided and this application filed July 29, 1926. Serial No. 125,630.

This invention relates to building blocks.

In my co-pending application, Serial No. 99,076, of which this application is a division, I disclosed therein a system of heating, 5 drying or cooling buildings wherein the walls were formed of hollow building blocks. The hollow building blocks at present constructed are not adaptable to carry out such a system in an efficient manner.

10 One of the objects of this invention is the construction of a hollow building block which will permit of its utilization as a conduit for a system of heating, drying or cooling buildings.

15 Another object of this invention is to provide building blocks having means for centering and locking one with respect to the other. Still another object of this invention is to provide building blocks having 20 communicating passages. Still another object of this invention is to provide a building block adapted to receive beam supporting means.

Referring to the drawings:

25 Figure 1 is a perspective view of a building block embodying the principles of my invention.

Figure 2 is a plan view of a section of a wall formed of blocks embodying the principles of my invention.

30 Figure 3 is a cross sectional view of a building block.

In carrying out my invention, I propose to provide a hollow building block of plastic 35 material such as hollow tile, cement, etc., of a special construction.

Block 1 is hollow and divided centrally and horizontally thereof into four compartments separated by intersecting dividing 40 walls 2, 2', which also function as strengthening ribs. Centrally of block 1, I provide a passage 3 communicating with the compartments and terminating in openings in the walls of the blocks. At the end of each 45 block the top and bottom wall and dividing wall 2 have semi-circular cutout portions to form half of a passageway 3' similar to passageway 3. A removable collar 4 is adapted to fit in passages 3, 3', of the top and bottom 50 walls of block 1. Removable collar 4 has neck portions 4', 4''. The neck portions fit into the openings of passage 3 or 3', of the block in the tiers above and below.

I propose to provide a special corner block 55 8 having a hollow central passage 9 there-

through. Corner block 8 forms an angle and terminates in two U shaped ends adapted to receive corresponding shaped lugs 10 carried by wall blocks 11 at one end. Central passages 9 can be filled with reinforced 60 cement if desired. The locking wall block 11, is keyed to the adjacent wall blocks by collars 4.

It will be noted that in laying the blocks the necks 4', 4'' of collars 4 are inserted in the passages 3 or 3', the mortar being laid or spread on the top surface up to the height of the collar portion 4 which acts as a gauge as well as a centering and locking device not only for the adjacent tiles but 65 also for the tiles forming the tier above. The collars 4 close the openings in the blocks 1, and thereby prevent the mortar 12 from being inserted into the hollow interior and the necks 4', 4'' extending above the height 70 of the mortar, none of the latter can drop into passages 3 or 3'. It should be further noted that such a construction permits of the insertion of angle supports 13 between two tiers of blocks 1, and the imbedding of such 75 supports in the mortar. These angle supports operate to carry the beams 7.

I preferably make collars 4, separable and not integral with the blocks in order to permit of a readier and cheaper shipment and 80 to prevent breakage.

I will thus be seen that I have shown a building block of strong and cheap construction having passages therethrough to permit of use in connection with the system of 85 heating and ventilating buildings and having centering and interlocking means.

What I claim is:

1. A building wall comprising hollow building blocks, openings in the top and bottom walls of said building blocks, semi-circular cutout portions at the ends of said walls of said building blocks in combination with hollow cylindrical collars, said collars in the wall openings of one tier of 95 blocks and in the opening formed by the junction of the semi-circular cutout portions of the adjacent blocks in the superposed tier.

2. A building wall, comprising tiers of 100 hollow blocks, the ends of said hollow blocks having semi-circular cutout portions forming a cylindrical opening in the top and bottom walls of the blocks, openings in the top and bottom walls of the blocks centrally 105

thereof in combination with hollow locking and centering means fitting in the wall openings of one tier and in the cylindrical openings formed by the junction of the cutout 5 ends of the superposed tier of hollow blocks.

3. A building wall composed of hollow blocks, said hollow blocks having interior strengthening walls forming longitudinal compartments therein, the wall ends of said 10 building blocks having cutout cylindrical portions, the strengthening walls having cut-

out cylindrical portions in alignment with the cutout cylindrical portions of the top and bottom walls, said cutout portions forming a cylindrical passageway through the 15 junction of each pair of blocks in each tier in combination with hollow centering and locking means fitting in said cutout portions.

Signed at New York, in the county of New York and State of New York, this 15th 20 day of July, A. D. 1926.

EUGENE LUCAS.
